(57) **CLAIM**

The ornamental design for a tire tread, as shown and described.

DESCRIPTION

FIG. 1 is a front perspective view of a tire tread; FIG. 2 is a front elevational view of the tire tread of FIG. 1; FIG. 3 is a rear elevational view of the tire tread of FIG. 1; FIG. 4 is a right-side elevational view of the tire tread of FIG. 1;

FIG. 5 is a top plan view of the tire tread of FIG. 1; FIG. 6 is a bottom plan view of the tire tread of FIG. 1; FIG. 7 is an enlarged perspective view of a portion of the tire tread of FIG. 1;

FIG. 8 is an enlarged front elevational view of a portion of the tire tread of FIG. 2;

FIG. 9 is an enlarged rear elevational view of a portion of the tire tread of FIG. 3; and,

FIG. 10 is an enlarged right-side elevational view of a portion of the tire tread of FIG. 4.

The broken lines are included for the purpose of illustrating portions of the tire tread that form no part of the claimed design.
